UNITED STATES PATENT OFFICE.

FRANK BEDARD, OF FLINT, MICHIGAN.

TELESCOPE AIR JET.

Application filed August 14, 1925. Serial No. 50,249.

This invention relates to new and useful improvements in paper making machines, and particularly to attachments for Fourdrinier paper making machines.

It is well known that as the paper reaches the first press rolls, a certain quantity of the pulp adheres to the screen belt, because of the fact that the operator cannot separate the paper from the belt, quickly enough, to start the paper through the pressing rolls, beyond the first ones. This pulp causes a deterioration of the screen belt, if not removed at once, and to remove the same, the ordinary methods consist in discharging water showers on the lower lap of the belt, and collecting the water and detached pulp in suitable boxes, from whence it escapes to suitable means where it is pumped back into the main supply tank, or chest. A comparatively large amount of this pulp is lost, through the use of the water showers, and it is the principal object of the present invention to provide means for separating this pulp from the wire screen belt, whereby the loss of the pulp is reduced to a minimum.

Another object of the invention is to provide a pneumatic means for separating the pulp from the screen, and wherein the force of the air is such that proper and quick separation is accomplished.

Another object is to provide a device of this character wherein the air delivered from the discharge nozzle is of equal force throughout the entire width of the screen belt, thereby insuring the complete separation of the pulp from the screen, with the minimum loss thereof.

Other objects and advantages will be apparent from the following description when taken in connection with the accompanying drawing.

In the drawing:

Figure 1 is a side elevation of a portion of a Fourdrinier paper making machine, showing the invention applied thereto.

Figure 2 is a plan view of the air nozzle, a portion of the lower press roll, and screen belt being broken away.

Figure 3 is an enlarged vertical longitudinal sectional view through the air nozzle.

Figure 4 is a vertical transverse sectional view through the air nozzle.

Referring particularly to the accompanying drawing, 10 represents a portion of the frame of a Fourdrinier paper machine, on

which are mounted the upper and lower couch rolls 11 and 12. Engaged around the lower roll 12, and contacting with the lower side of the upper roll 11, is the wire screen belt 13, on which the paper is formed, and from which the operator must quickly separate the paper, as the belt passes around the outer side of the said lower roll. On each side of the frame 10, below, and inwardly of the lower roll 12, are mounted the brackets 14, and supported in these brackets, and extending transversely above the lower lap of the screen belt, is the air nozzle, represented as a whole by the numeral 15.

The nozzle includes an outer cylindrical body 16, externally threaded on each end, and having the caps 17 and 18 screwed thereon. In the center of the cap 17 is an opening 19 through which is disposed a second cylindrical body 20, smaller diameter than the outer one, and spaced from the inner wall thereof. This second body or tube 20 is externally threaded on each end and has the caps 21 and 22 screwed thereon, said tube being of greater length than the tube 16 so that the end which carries the cap 21 projects a certain distance through the cap 17. A third tube 23 is disposed within the tube 20, and has one end projecting through the central opening 24, in the cap 21, where it is externally threaded to receive a suitable connection to a supply of air, not shown. The other, or inner, end of the tube 23 is externally threaded and carries the cap 25. Disposed transversely through all of the caps 17, 21, and 25, and the adjacent ends of the tubes, is a bolt 26, which maintains the tubes against slidable or rotatable movement with respect to each other. In the lower side of the outer tube 16 there is formed a longitudinal slot 27, of a length approximating the distance between the caps 17 and 18. In the second tube 20 there is formed a longitudinal slot 28, of a length equal to the slot 27, but of a width approximately twice that of the slot 27. In the innermost tube 23 there is formed a longitudinal slot 29, of a length equal to the other slots but having a width twice that of the slot 29. Thus the slots, range greater in width progressively toward the inner tube, so that the slot of the outer tube 16 is one-fourth that of the slot of the tube 23. Within the caps 17 and 24 are arranged the packing members 30 and 31, respectively, with

which the adjacent ends of the tubes 16 and 20 bear to render an air-tight joint. It will be noted that the slots are disposed in the respective tubes at points diametrically opposite to the slot of the next adjacent tube, and that the tubes are spaced from each other to form air chambers in which to permit air to collect, so that the air delivered from the external source will not be driven directly through the slots of the nozzle, but issue from the outer slot at a uniform pressure throughout the entire length of the slot. It will be noted that the slot 27 is disposed in close proximity to the upper face of the lower lap of the screen belt, at a point adjacent the lower couch roll, so that the air discharged therefrom will pass through the belt, to dislodge the paper from the screen and blow the same into a suitable receptacle 32 located therebeneath.

Particular attention is called to the construction and arrangement of the tubes, and the differences in widths thereof, whereby to cause a constant stream of air to flow from the outer slot 27, and with equal force throughout the entire length of the slot. Furthermore, the disposition of the slots, wholly within the space between the caps 17 and 18, and the particular spacing of the tubes from each other, provides for a series of air chambers in which the air will collect under pressure, so that it will issue from the slots with equal force at all points along the slots.

What is claimed is:

1. The combination with the screen belt of a paper machine, of a device for projecting air against the screen to remove adhering pulp therefrom comprising telescopically arranged and spaced chambers having communication with each other and having an outlet for directing the air against the belt. 35
2. The combination with the screen belt of a paper machine, of a device for projecting air against the screen to remove adhering pulp therefrom comprising a series of telescopically arranged and spaced tubes, each of the tubes having a longitudinal slot, the slots of the tubes being progressively 40 smaller in width toward the outermost tube. 45
3. A nozzle for directing air against the screen belt of a paper making machine comprising a plurality of telescopically arranged and spaced tubes, said tubes being 50 terminally closed, the innermost tube having connection with a source of air, each of the tubes having a longitudinally extending slot arranged at a position diametrically opposite to the slot of each of the other tubes, adjacent thereto, the slot of each tube being of 55 greater width than the slot of the next tube therewith, whereby air will accumulate between the tubes and issue from the slot of the outermost tube at a constant pressure 60 throughout the length of the slot. 65

FRANK BEDARD.
